(57) **CLAIM**

We claim the ornamental design for a lid and screen assembly of a sample collection container with screen, as shown and described.

DESCRIPTION

FIG. 1 is a top perspective view of the first embodiment of a lid and screen assembly of a sample collection container with screen showing our new design with the lid and screen portions connected;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top perspective exploded view of the second embodiment of the lid and screen assembly of a sample collection container with screen with the lid and screen portions separated;

FIG. 18 is a bottom perspective exploded view thereof;

FIG. 19 is a front elevational exploded view thereof;

FIG. 20 is a rear elevational exploded view thereof;

FIG. 21 is a left side elevational exploded view thereof;

FIG. 22 is a right side elevational exploded view thereof;

FIG. 23 is a top plan exploded view thereof; and,

FIG. 24 is a bottom plan exploded view thereof.
